UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SHOE BOTTOMS.

Application filed November 23, 1918. Serial No. 263,894.

This invention relates to machines for use in the manufacture of shoes and is illustrated herein as embodied in a heel seat fitting machine.

5 In the manufacture of shoes having wood heels it is customary to trim away the edge of the heel seat portion of the sole so that the edge of the sole will be covered and concealed by the upper edge of the heel which, 10 accordingly, bears directly on the shoe upper. When trimming away the margin of the heel seat portion of a sole it is usual and desirable to trim the sole to a shape corresponding to that of the cavity of the attaching face of the wood heel which is to be attached, thus providing a firm foundation for the heel so that the heel can be securely attached to the shoe without danger of a crack opening up between the edge of the heel and the shoe upper. It is usual also as 15 a part of the heel seat fitting operation to form a pair of heel breast receiving shoulders at the heel breast line, these shoulders thus being positioned at the forward extremities of the trimmed-away portion.

20 It is an object of the present invention to provide an improved heel seat fitting machine of a character readily adaptable to fit the different sizes and styles of shoes 25 which it may be desired to operate upon.

With this object in view, a feature of the invention, as embodied in the illustrated machine, comprises a movable cutter operative to trim surplus stock from the heel seat portion of the sole of a shoe, and adjustable means, illustrated as a cam, to guide the cutter as it performs the trimming operation. Thus the path of the cutter can be varied in accordance with the size and shape to 30 which the heel seat of the sole is to be trimmed. In the illustrated machine adjustable means are provided both for varying the convexity (as viewed in cross-section) to which the heel seat is trimmed, and for 35 varying the curve of the heel breast receiving shoulder relatively to a vertical axis forward of the heel breast line.

In the preferred form of the invention the controls for determining the path of the cutting means are effective to move said means in a three dimensional curve or space curve which is generally defined as a curve not lying in a single plane, producing a heel-breast cut which curves in three dimensions

and can thus be joined perfectly to a heel having a concaved breast.

A further feature of the invention comprises a cutter or cutters movable widthwise of the sole of a shoe for cutting a heel breast receiving abutment at each edge of the sole, 60 these abutments being located at the heel breast line. The illustrated machine is provided with a knife having two pairs of angularly related cutting edges one pair of which operates upon one edge of the sole and 65 the other pair of which operates upon the other edge of the sole. By the operation of this cutter the heel breast receiving shoulder is formed and the adjacent portion of the periphery of the heel seat is beveled simultaneously, the operations being performed successively on the two sides of the heel seat 70 while the shoe is firmly supported and clamped in place.

To aid in supporting the edges of the heel seat of the sole during the heel seat fitting operation the illustrated machine, in accordance with another feature of the invention, is provided with a pair of jaws, one on each side of the shoe in the vicinity of the heel 80 breast line, arranged to enter the rand or welt crease of the shoe to support the edges of the sole at the heel breast line during the heel seat fitting operation.

The machine herein disclosed is particularly adapted to operate upon shoes of the type having a short outsole and a heel the attaching face of which is provided with a cavity for the reception of the end of the short sole, this cavity extending only a fraction of the distance from the breast of the heel to the rear, as disclosed in Letters Patent of the United States, No. 1,396,801, granted November 15, 1921 on an application filed by the present applicant. It 95 should be understood, however, that this is primarily for purposes of illustration, and that in various of its aspects the invention is not limited in its utility to embodiment in machines for operating upon the soles of 100 shoes of this type. On the contrary, various of its features are applicable also to machines for performing the heel seat fitting operation upon shoes having full length soles which are to have attached to them wood heels of any of the usual types.

With the above and other objects and features in view, the invention will now be de-

scribed in connection with the accompanying drawings and pointed out in the claims.

Figure 1 is a view in side elevation of the machine; Fig. 2 is a view in front elevation thereof; Fig. 3 is a top plan view thereof; Fig. 4 is a sectional view taken substantially on the line 4—4 of Fig. 1; Fig. 5 is a fragmentary view of the machine in front elevation, showing a portion of the movable knife support with the knives in the position they occupy at the end of one of the cutting operations and illustrating also the effect of the cutting operation on the outsole; Fig. 6 is a view partly in section on the line 6—6 of Fig. 1, showing the movable parts indicated in Fig. 5 in the positions they occupy before the shoe is placed in position and the machine started; Fig. 7 is a view partly in section on the line 7—7 of Fig. 1; Fig. 8 is a view similar to Fig. 7, showing a different adjustment of the flexible guiding device or cam for controlling the movement of the knives; Fig. 9 is an enlarged detail view of the flexible cam; Fig. 10 is a view partly in section on the line 10—10 of Fig. 1; Fig. 11 is a sectional view taken on the line 11—11 of Fig. 3; Fig. 12 is a top plan view of certain of the parts shown in Fig. 11; and Fig. 13 is a perspective view of the oscillatory head that supports the sole scarfing cutter, the support for the shoe bottom to be operated upon being omitted to clearly illustrate the cutter.

A concrete example of the nature of the heel seat fitting operation that is the result of using this machine of the present invention, is disclosed in said Winkley Patent No. 1,396,801 dated November 15, 1921, and for the sake of simplicity and clarity the fitting of a short outsole of that type will now be described, but those skilled in the art will recognize that the features of the illustrated machine may be variously modified within the skill of the artisan to adapt the invention to a similar fitting of other kinds of outsoles.

In the preferred embodiment of the invention illustrated in the drawings, the machine comprises in general, a frame, upon which the various parts of the operating mechanism are mounted, consisting of a rectangular body portion 14 and a supporting frame or standard 16; an adjustable back gage 18 (Fig. 1) against which the heel of the shoe is placed to determine the longitudinal position of the shoe with respect to the knives; a plurality of pivotally mounted or laterally swinging arms 20 (Fig. 2) which are geared together and provided with gripping jaws 22 (Fig. 6) which cooperate, when the arms are swung toward each other, to support and position the shoe laterally with respect to the knives; outsole supporting fingers 24 (Figs. 2, 5 and 6) mounted, one on each of the swinging arms, for entering

the welt crease at opposite sides of the shoe and providing a rigid support for the lateral edges of the tongue at the shank end of the outsole while it is being operated upon by the knives; a mechanism for swinging in 70 the pivotally mounted arms 20 so that the gripping jaws 22 will position and support the shoe, and the outsole supporting fingers will support the opposite lateral edges of the tongue of the outsole, said mechanism including a treadle 26, whereby the operation of the machine is controlled; a locking device, including a lever 28 (Fig. 1) connected with the treadle, for locking the swinging arms 20 in operative position; a pair of heel-seat fitting knives 30 and 32 (Figs. 6 and 13) for scarfing or beveling the tongue of the outsole, the knives being located at the front of the body portion of the frame and mounted in such a manner that they may be brought alternately into position to operate upon opposite sides of the outer face of the tongue; an oscillatory head 34 which is mounted in said body portion of the frame and carries the heel seat fitting 75 knives 30 and 32 and which is oscillated about adjustable pivot blocks 36 (Figs. 4 and 11) to cause the knives to convexly scarf or bevel the outer face of the tongue; a mechanism, including a crank 38 (Figs. 4 and 11) for oscillating the head 34 alternately toward opposite sides of the machine; a flexible guiding device or cam 40 (Figs. 7, 8, 9, and 13) having the dual function of supporting the head 34, which is free to move radially with respect to the pivot blocks 36, and of modifying the oscillatory movement of the head so that the knives will produce the required convex curvature of the outer face of the tongue; a gaging device 100 consisting of a curved strap cam 42 (Figs. 2, 11, and 12) for varying the position of the knives angularly and longitudinally with respect to the sole, during the performance of their cutting operations, so as to produce curved shoulders adjacent to the scarfed or beveled portion of the tongue, which are shaped to fit the curve of the breast of the heel; a mechanism including shift levers 44 and 46 (Figs. 2, 5 and 6) whereby the knives 105 are shifted during each cycle of the machine so as to bring the knives successively into operative position; a one revolution clutch 48 (Fig. 10) for connecting and disconnecting the machine to and from the source of power; and means under control of the operator for operating the clutch.

Power is continuously supplied, from a suitable source to a drive pulley 50 (Figs. 1 and 3) which is loosely mounted on the rear end of a main shaft 52 that is suitably journaled in the supporting standard 16. The main shaft is normally idle and may be connected to the continuously driven pulley 50 by means of the clutch 48. The vari-

ous operating mechanisms of the machine are connected to a cam shaft 54 which is driven from the main shaft 52 through gearing 56 (dotted lines Fig. 1), a counter-shaft 58 and gearing 60.

The shoe to be operated upon is placed with its heel end against the back gage 18 and with the shank portion of the outsole bearing upwardly against that one of the 10 two knives 30, 32, which is in operative position. The location of the back gage determines the longitudinal position of the shoe relatively to said knife and the gage is adjusted according to the size of the shoe 15 to be operated upon so as to bring the tongue of the outsole into the path of both of the knives.

The back gage consists of the long, irregularly shaped arm 18 which is secured to 20 one end of a short shaft 62 (Fig. 1) mounted in a fixed bearing 64. The upper end of the back gage is supported against lateral displacement by the sides of a groove 66 (Fig. 7 and 8) formed in the under side of 25 a bracket 68 that is fixed to the frame. The back gage is adjusted forwardly and rearwardly in the groove 66 by means of a handle 70 (Fig. 1) that is pivotally connected at 30 72 to an arm 74 secured to the opposite end of the shaft 62. The movement of the handle is controlled by a segment 76 having an 35 arcuate slot 78 therein which receives a pin 80 projecting laterally from the handle. The slot, being eccentric to the pivot 72, movement of the handle results in rocking of the shaft 62 and in the longitudinal adjustment of the back gage. The outer face of the segment 76 is provided with teeth adapted to 40 be engaged by a suitable detent (not shown) on the handle so as to hold the handle and the back gage in adjusted position.

During the cutting operation the shoe is supported at the back between the gripping jaws 22 carried by the free ends of the 45 swinging arms 20, the jaws being provided with gripping surfaces, formed of resilient material, which conform somewhat to the contour of the lasted shoe when pressed against the sides thereof. On each swinging arm 20 adjacent its gripping jaw 22 is 50 one of the outsole supporting fingers 24 so shaped that the extremity thereof will enter the welt crease of the shoe between the edge of the tongue on the outsole and the upper. 55 The fingers 24 are pivoted at 82 (Fig. 6) to a plate 84 that is adjustably secured to the front of the swinging arm 20 by means of a screw 86 which projects through a slot 88 in the plate and into the arm 20. In order 60 that the fingers 24 may be accurately adjusted longitudinally of the arms 20 so as to insure they will enter the welt creases of different styles of shoes, each plate 84 is provided with a suitable adjusting screw 90 (Fig. 2). The screw 90 is free to turn in

a lug 92 on the arm 20, but is prevented from moving longitudinally therethrough, and is received in a threaded aperture 94 in the plate 84. The fingers 24 are yieldingly pressed toward each other by springs 96 the 70 ends of which are confined in sockets, one in the finger and one in the plate 84.

The swinging arms 20 are secured to shafts 98 (Fig. 2) to which are also secured intermeshing gears 100. The shafts 98 are 75 mounted in bearings 102 formed on a casing 104 which encloses the gears and is bolted to the frame. The means for swinging the arms into and out of operative position comprises an arm 106 that is fixed to the shaft 80 98 on the right hand side of the machine (Fig. 2) and connected by a universal joint 108 with a rod 110. Yielding operative connections are provided between the rod 110 and the treadle 26 comprising a spring 112 85 and an arm 114, the latter pivoted at 116 to the treadle, the rod passing freely through an aperture in a lug 118 formed at the upper end of the arm and the spring surrounding the rod and being interposed between a 90 collar 120 at the lower end thereof and the lug 118. By means of this construction the treadle, which is depressed to cause the shoe to be gripped by the jaws 22 on the swinging arms 20, may thereafter be further depressed 95 to operate the clutch and start the machine.

After the shoe has been placed with its heel end against the back gage and the outsole in contact with the knife which is central (see Fig. 2), the operator depresses the 100 treadle 26 and the arms 20 are swung inwardly so that the gripping jaws 22 engage the shoe, one on either side thereof, positioning the shoe laterally with respect to the knife and supporting it in position to be 105 operated upon. As the swinging arms move inwardly toward the shoe, the ends of the outsole supporting fingers 24 enter the welt-crease between the tongue extending from the shank end of the outsole and the portion of the upper which has been lasted over the insole, as shown in Figs. 5 and 11, supporting the corners formed by the junction of the tongue and shank portion of the sole. The springs 96 permit the fingers to 110 yield laterally so as to adjust themselves readily to the shoe but when the fingers are in position with their ends beneath the end of the outsole they provide a rigid support therefor, resisting unyieldingly the downward pressure of the skiving knives and permitting them to scarf the tongue down to a uniformly thin edge at the said corners.

When the swinging arms 20 have been moved into their operative position, they are 115 locked thereon so that a subsequent release of the treadle will not permit the release of the shoe until the cycle of operations has been completed. The locking means comprises a cam 122 (Fig. 1) on the cam shaft 54 hav-

ing its cam surface at the rear end face thereof and which cooperates with the locking lever 28 that is fulcrumed on a stud 124 and connected at 126 with a rod 128 which 5 is pivoted to an arm 130 on a rock shaft 132 to which the treadle is also fixed, and which is mounted in suitable bearings in the frame. A cam notch 134 in the face of the cam 122 is normally occupied, when the machine is idle, by the free extremity of the locking lever 28, thus permitting a spring 136 to raise the treadle 26 into its normal 10 inoperative position. When, however, the treadle is depressed sufficiently to cause the shoe to be gripped by the gripping jaws 22, the locking lever 28 will be swung out of the notch 134 in the cam. Further depression of the treadle will cause rotation of the cam shaft, as will be hereinafter described, and as the cam turns, the notch 134 will be carried out of registry with the locking lever, as shown in Fig. 1. If the treadle is released before the completion of the cycle the free extremity of the locking lever 25 will be prevented from returning to its normal position by the face of the cam and the swinging arms 20 will thus be locked in their gripping positions against the shoe. At the completion of the cycle, the cam 30 shaft will have made one complete revolution and brought the notch 134 again in registry with the end of the locking lever. The end of the locking lever will then be free to enter the notch and the tension of 35 the spring 136 will raise the treadle and release the shoe.

The cutting or scarfing operation is performed by the two knives 30 and 32 (Figs. 6 and 13), each of which is provided with 40 two cutting edges 140 and 142 that are angularly disposed the one to the other, as shown best in Fig. 13. The vertical cutting edges 140 of the knives are adapted to produce the shoulder formed to engage and closely fit 45 the breast of the heel and the horizontally disposed cutting edges 142 extend substantially the length of the tongue and function to skive or scarf the respective sides thereof in such manner as to provide a substantially 50 convex heel seat at the outer or bottom face of the tongue to conform to the contour of the base of the recess in the heel.

When the shoe is gripped in position as 55 already explained, the knives 30 and 32 are given a swinging movement transversely across the tongue of the outsole through the agency of the head 34 (Figs. 4, 11 and 13) which carries them. The knives are moved alternately toward opposite sides of the machine by means of the crank 38 (Figs. 11 and 18) which is oscillated through intermediate 60 mechanism by a cam 144 on the cam shaft 54, as will hereinafter appear, and they operate successively, one to cut or scarf one 65 side of the tongue of the outsole, as the head

swings in that direction, and the other to scarf the opposite side of the tongue during the swinging of the head in the opposite direction toward the corresponding side of the machine.

In order that each knife may be brought into position to perform its cutting or scarfing operation upon the proper side of the tongue prior to the swinging of the head toward that side of the machine, both knives 70 are mounted on a single knife-block 146 which is pivotally mounted on a horizontal stud 148 extending from a lug 150 (Fig. 11) which depends from a post 152. The knife block 146 is adapted to be shifted to move 75 the knives from one operative position to another by mechanism hereinafter described and is provided with two shoulders 154 (Fig. 6) which are adapted to co-operate with stops or shoulders 156 on the post 152 80 for the purpose of limiting the extent of movement of the knife block, while a spring pressed detent 158 is provided in an orifice at the base of the post 152, the engagement of the detent with one of two positioning 85 notches 160 in the upper surface of the knife block serving to hold the knives in their operative positions.

The knives are mounted on the knife block 146 with their unsharpened longitudinal 90 edges toward each other, as shown in Fig. 6, each knife being adjustably secured thereto by means of a screw 162, which extends through a slot 164 in one of the angularly disposed portions of the knife, and into the 95 knife block. The hub portion of the knife block through which the stud 148 extends has a semi-cylindrical surface 166 (Fig. 11) which bears against the wall of a cylindrical recess in the bottom of the post 152 which 100 serves to relieve the strain on the lug 150 during the cutting operation.

The swinging movements of the knives 30 and 32 are transmitted thereto from the head 34 through a knife supporting arm 168 (Figs. 1, 2, 11 and 13) which is carried by the head and provided with a bearing 170 at its forward end, in which is journaled the post 152, the post being supported in the said bearing by a collar 172 which is 110 pinned to the post and engages the upper end of the bearing 170.

The oscillatory head 34 is constructed of two plates 174 and 176 (Figs. 7, 8, 11 and 13) that are rigidly connected by a cross-bar 178, the plates being guided to permit the head to swing laterally in a vertical plane between two struts 180 (Figs. 4, 7 and 11) extending transversely across the body portion 14 of the frame, the inner sides of the struts forming bearing surfaces which co-operate with the outer surfaces of the plates 174 and 176 as the head is oscillated and prevent longitudinal or angular displacement of the head. The head is supported by the flexible cam 120 125 130

40 which is mounted upon the bracket 68 and upon which rests a cam roll 182 carried by the plate 174 of the head 34.

The knife supporting arm 168 (Figs. 1, 2, 5 11, and 13) is fixed on one end of a hollow shaft 184 which is mounted with provision for longitudinal movement in bearings 186 at the top of the cross-bar 178 of the head 34 and is urged forward by a spring 188 that 10 is confined within the hollow shaft 184 between the solid front end thereof and a thimble 190 which is adjustably held in the rear bearing 186 by means of bolts 192. The hollow shaft 184 is prevented from turning in 15 its bearings as the knives are swung from side to side of the machine with the head 34 by means of a collar 194 that is fixed on the shaft between its bearings 186 and has a flattened under surface which cooperates 20 with a machined bearing surface 196 on the top of the cross bar 178.

The longitudinal movements of the knife supporting arm 168 develop a certain amount of end thrust and, in order to prevent the 25 thrust from causing the head 34 to bind or be cramped in its bearings, adjacent to the outer faces of the plates 174 and 176 an additional bearing is provided for the head. This bearing consists of an arched frame 198 which is constructed of two members that 30 project upwardly from the frame 14 and are bolted together and so formed as to provide a groove 200 at the inner periphery of the arched frame to receive a tongue 202 (Figs. 35 11 and 13) projecting upwardly from the forward plate 174 of the head. As the head 34 swings laterally of the machine the tongue 202 moves freely in the groove 200 and the 40 end thrust of the head is taken up by the arched frame member on opposite sides of the groove.

In order to provide for the oscillation of the head 34, each of the plates 174 and 176 is formed with inward projections 204 (Figs. 45 4 and 11) between which is a slot 206 extending vertically through the center of the plate. In each slot 206 is guided one of the two pivot blocks 36, and the said blocks are pivotally connected at 208 between the inner 50 ends of a yoke frame 210 (Figs. 4 and 13) by means of which they are adjusted in the slots. The opposite end of the yoke frame 210 is pivoted to a link 212 which is, in turn, pivoted at 214 between ears rising from the frame. A curved link 216 is pivoted to the frame of the machine at 218 and to the yoke frame at 220 and the proportion and arrangement of the links 212 and 216 and the yoke frame 210 is such that by virtue of 55 the movement thereof the pivot blocks 36 are constrained to move only in a vertical path. The end of the yoke frame which carries the pivot blocks is connected through a universal joint with a link 222 pivotally connected 60 with a lever 224 (Fig. 1), this lever being

fulcrumed on the stud 124 on which locking lever 28 is mounted and is provided with an operating handle 226. The handle 226 is operated to shift the position of the pivot blocks 36 in the slots 206 and is provided 70 with suitable locking means 228 cooperating with a stationary segment 230 whereby the lever 224 and the pivot blocks 36 are locked in their adjusted positions.

The head 34 is oscillated by means of the 75 crank 38, (Figs. 4, 11 and 13) which is arranged at the rear of the plate 176 of the head and has a crank pin 232 connected with a slide block 234 that is mounted in the slot 206 in the plate 176. The crank 38 is fixed 80 to a crank shaft 236 that is mounted in bearings 238 on the frame 14. The teeth of a pinion 240 which is also fixed to the crank shaft, are in mesh with the teeth of a rack bar 242 which is pivotally connected at its 85 lower end to a cam lever 244, the lever being pivoted at 246 to the frame and provided with a cam roll 248 that is operated by the grooved cam 144 on the cam shaft 54. The teeth of the rack bar are held in mesh with 90 the teeth of the pinion by means of a flanged roll 250 that is supported from the frame and arranged to bear against the side of the rack bar farthest from the pinion. The cam 144 is designed so that during each cycle of 95 the machine the head 34 will be swung about the pivot blocks 36 first toward one side of the machine and then toward the opposite side thereof. As the head 34 and the knife block 146 which is carried thereby are swung to each side of the central position the knives operate successively, so that one of the lateral portions of the tongue is beveled and then the opposite lateral portion thereof is similarly treated.

The desired convex curvature of the outer or bottom face of the tongue is produced by modifying the oscillatory movement of the head 34 by means of the supporting and guiding device or the cam 40. This cam 110 consists of a flat stiff spring which is flexed to give it the required contour by means of fingers 254 (Figs. 7, 8, and 13), which are adjustably mounted on the frame 14 at each side of the cam supporting bracket 68 and engage opposite ends of the cam. The contour of the cam 40 is such as to effect a slight shifting of the head relatively to the pivot blocks 36 as the cam roll 182 rides over the cam during the oscillation of the head. The knives 30 and 32 are thus caused to travel through a path determined by the contour of the cam and the tongue is skived or scarfed so that the curvature of its outer 115 face corresponds to that of the base of the recess in the heel. The cam 40 is preferably constructed in such a manner that when flexed by the fingers 254 it will have a contour slightly more rounding near its ends than at its central portion. This may be 120 125 130

accomplished by making the central part of the cam thicker and consequently stiffer than the ends, as shown in Fig. 9.

The following provision is made for varying the curvature of the outer face of the tongue, produced by the skiving knives, as required in different styles of shoes. The fingers 254, by means of which the cam 40 is flexed, are carried by blocks 256 fixed at the top of vertical posts 258 (Figs. 7 and 8) which project through and are guided by ears 260 projecting inwardly from the frame 14. Pivotally connected to the finger blocks 256 are the members 262 carried by vertical connecting rods 264 which are, in turn, connected to arms 266 (Fig. 1) on a rock shaft 268. Fixed to the rock shaft between the arms 266 is an arm 270 bearing a cam roll 272 which is engaged by a cam face 274 (dotted lines Fig. 1) that is formed on the under side of the lever 224 by which the pivot blocks 36 are adjusted. By means of the handle 226 of the lever 224 the cam 40 is flexed and the pivot blocks 36 are adjusted at the same time. The cam face 274 is designed to give the required amount of flexure to the cam 40.

In order to have the vertical shoulder which is formed at the base of the tongue curved to accommodate itself to the curve of the breast of the heel, a gaging or guiding device consisting of the curved strap cam 42 (Figs. 5 and 12) is provided, which is removably secured by bolts 276 to the front of the body portion of the frame 14. This strap cam 42 is engaged by cam rolls 278 carried by a yoke frame 280, the sides of which are in the form of bell crank levers pivoted at 282 (Fig. 1) on opposite sides of the post 152, the forwardly extending arms of the levers being united by the transverse central portion of the frame (see Fig. 3). The cam rolls 278 are mounted at the lower ends of the two downwardly extending arms of the yoke frame 280 and a set screw 284 which is provided at the transverse central portion of the frame is adapted to engage a lug 286 on the post 152. The expansion spring 188 (Fig. 11) within the hollow shaft 184 forces the knife supporting arm 168 together with the post 152 and the knife block 146 forwardly, thus holding the cam rolls 278 in contact with the curved strap cam 42 and the set screw 284 in contact with the lug 286. The cam 42 curves forwardly, corresponding to the curve of the breast of the heel, and as the knives swing to one side with the head they are moved forwardly by the force of the spring 188 as far as the post 152 is permitted to move by the cam 42. At the same time the knives are turned as the post 152 turns in its bearing 170 by reason of the rolls 278 assuming different positions relatively to the face of said cam 42, and as the head swings back

again the knives are returned to their normal position. If it is desired to vary the curve of the shoulder formed by the knives at the base of the tongue the cam 42 may be removed by unscrewing the bolts 276 and another cam having a different contour substituted therefor. By adjustment of the set screw 284 the longitudinal position of the knives relatively to the tongue may be varied, and a finer adjustment obtained than can be made by shifting the back gage 18.

In order to shift the knives 30 and 32 so as to bring their opposite cutting edges alternately into operative positions, the shift arms 288 and 290 (Fig. 6) are provided, extending outwardly from opposite sides of the knife block and perpendicularly to the pivot stud 148, and adapted to be engaged by the shift levers 44 and 46 respectively. The shift levers are severally provided with rolls 292 for engaging the shift arms and are fulcrumed upon studs 294 fixed in ears 296 rising from the frame. The shift levers are normally held in inoperative position with the rolls elevated by means of tension springs 298 which pull downwardly on extensions 300 of the levers. The levers are pivotally connected at points between the fulcrums 294 and the rolls 292 with vertical rods 302 (Fig. 2) which are pivoted at their lower ends to arms 304 on rock shafts 306 suitably journaled in the supporting frame 16. To the opposite ends of the rock shafts are secured upwardly extending curved arms 308 (Figs. 1 and 7) carrying cam rolls 310. One of the cam rolls is adapted to be engaged by a cam 312 (Figs. 1, 7 and 8) on the cam shaft 54 while the other is adapted to be engaged by a cam 314 on the cam shaft. The cams 312 and 314 operate independently to shift the knife block 146 while the swinging head 34 is in neutral position, the cam 314 acting to depress the shift lever 46 and through the shift arm 290 shift the knife block so that the knife 32 is brought into position to operate as the swinging head moves to the right, as shown in Fig. 6, while the cam 312 acts after the head has returned to neutral position to depress the shift lever 44 and through the shift arm 288 shift the knife block so that the knife 30 is brought into operative position as the head swings toward the left.

The clutch 48 (Fig. 10) by means of which the cam shaft is given one complete revolution for each cycle of the machine comprises a driven member consisting of a laterally projecting flange 316 on the pulley 50 and a driving member consisting of a split ring 318 which is supported at one end by a hub 320 that is keyed to the main shaft, the split ring being arranged to engage the interior surface of the flange 316. The ends of the ring are connected by a toggle comprising pivotally connected links 322 and 324, the toggle being

operated to engage the ring 318 with the flange 316 and to disengage the ring therefrom at the proper times. The link 324 of the toggle has an extension 326 which is engaged by a spring 328 that is confined between said extension and a projection 330 on the hub 320. The action of the spring tends to straighten the toggle and engage the ring 318 with the flange 316 but is prevented from doing so by a clutch releasing arm 332, that is pivotally mounted on a stud 334 on the frame of the machine. The arm 332 is held in position to compress the spring 328 by a stronger spring 336 that is connected between a stud 338 on the frame 16 and a pin 340 at one end of a bell crank lever 342, the spring acting through said bell crank lever and through a link 344 to force the clutch releasing arm 332 downwardly against a cam roll 346 on the extension 326 of the link 324.

The engagement of the clutch members is controlled by the treadle 26 which is fixed on the rockshaft 132 (Fig. 1) and has a rearwardly extending arm 27, that is adapted to engage the lower end of a rod 348 which is vertically movable in bearings 350 on the frame. When the treadle is depressed, the rod 348 is adapted to be lifted by the arm 27 against the action of a spring 352, surrounding the rod near its lower end and being interposed between a collar 354, that is fixed to the rod, and the lower bearing 350. Upon the release of the treadle the downward movement of the rod is insured by means of the spring 352 and the extent of the movement is limited by a stop collar 356. An arm 358 (Fig. 10) is pivoted at 360 to the upper end of the rod 348 and normally engages a depending lug 362 on a lever 364 which is fulcrumed on a stud 366 on the frame, the arm 358 serving to swing the lever 364 upwardly when the rod 348 is lifted. The lever 364 is connected by means of a rod 368 with the bell crank lever 342.

In order to start the machine after the shoe has been placed in position against the back rest 18, the operator depresses the treadle. The first part of the downward movement of the treadle causes the pivoted arms 20 to be swung into position to support the shoe. After this has occurred further depression of the treadle brings the arm 27 into contact with the bottom of the rod 348, and lifts the rod together with the pivoted arm 358, swinging upwardly the lever 364 and also swinging the clutch releasing arm 332 upwardly through the connections comprising the link 344, the bell crank lever 342 and the rod 368.

The upward movement of the clutch releasing arm 332 permits the spring 328 to straighten the toggle consisting of the links 322 and 324 sufficiently to force the members of the driving clutch into engagement,

whereby the cam shaft of the machine is then driven in the direction indicated by the arrow in Fig. 10, by means of the gearing 56, the countershaft 58 and the gearing 60, through a cycle of operations in which the knives are actuated to scarf or bevel the tongue of the outsole.

During the greater part of the cycle of operations, the lever 364 is supported in its raised position irrespective of the continued maintenance of pressure on the treadle by the operator, by means of a cam 370, the high part of which comes beneath the cam roll 372 immediately after the machine starts. The clutch releasing arm 332 is also held in raised position through the connections between said arm and the lever 364. Subsequent release of the treadle, therefore, will not effect the disengagement of the clutch members and premature stopping of the machine.

In order to interrupt the operation of the machine at the end of each cycle the cam 370 is designed so that it will permit the return of the lever 364 to its normal position and the coincident movement of the clutch releasing arm 332 into position to effect the disengagement of the clutch members in time to cause the stopping of the machine after the cam shaft has completed one revolution. The disengagement of the clutch members is effected by a cam face 374 on the clutch releasing arm 332 which is in the path of the cam roll 346 on the extension of the toggle link 324 when the clutch releasing arm is in its normal position. As the rotation of the main shaft 52 carries the roll 346 over the cam face 374 the toggle links are swung inwardly, the spring 328 being compressed by the force of the stronger spring 336.

In order to insure the stopping of the machine after a single revolution of the cam shaft, in case the operator continues to hold the treadle depressed, means is provided for swinging the arm 358 out of engagement with the lug 362 on the lever 364. This means comprises a cam 376 which is secured to the cam shaft 54 and is provided with a depression which is normally occupied by a cam roll 378 on the arm 358. After the arm 358 has been raised sufficiently to lift the lever 364 and start the cycle of operations, the rise in the cam 376 acts on the roll 378 to swing the arm 358 about its pivot, against the action of a spring 380 so that the top of the arm will clear the lug 362 on the lever 364, leaving the latter free to assume its normal position when permitted to do so by the cam 370.

After the treadle 26 has been released and the machine has been brought to rest at the end of a cycle of operations the various parts of the machine have been returned to their initial positions. The machine is then in readiness to act upon another shoe.

and to repeat the cycle of operations hereinbefore set forth.

While it is preferred to embody the invention in a machine having the specific construction and arrangement of parts herein shown and described, it will be understood that such construction and arrangement are not essential except so far as specified in the claims and may be modified without departing from the spirit and scope of the invention.

That which is claimed as new is:

1. A machine for operating upon a lasted shoe provided with an outsole having, in combination, means for supporting and clamping the shoe, and means for trimming the rear of the outsole successively on opposite sides to provide a convex heel-seat to fit a concave recess in a heel which is to be attached to the shoe.

2. A machine for operating upon a lasted shoe provided with an outsole having, in combination, means for completely supporting the shoe, means for trimming the rear of the outsole successively on opposite sides to provide a heel-seat to fit a recess in a heel which is to be attached to the shoe, and means for forming a shoulder adjacent to said heel-seat to fit the breast of the heel.

3. A machine for operating upon a shoe provided with an outsole having, in combination, means for supporting the shoe, means for scarfing a portion of the bottom face at the rear of said sole to provide a substantially convex seat for a heel which is to be attached to the shoe, and means for controlling the operation of said scarfing means to vary the convexity of the heel seat.

4. A machine for operating upon a shoe provided with an outsole having, in combination, a single means for supporting the shoe, means for trimming a portion of the bottom face at the rear of said sole operating successively on opposite sides of the sole to provide a seat for a heel which is to be attached to the shoe, and means for forming a shoulder adjacent to said trimmed portion to fit the breast of the heel, said trimming and forming means being arranged to operate on a shoe supported on said single supporting means.

5. A machine for operating upon a shoe provided with an outsole having, in combination, means for supporting the shoe, and an angular bladed knife for simultaneously scarfing the rear of said sole and cutting a shoulder adjacent to said scarf'd portion.

6. A machine for operating upon a shoe provided with an outsole having, in combination, means for supporting the shoe in fixed position, and means operating successively to bevel the opposite lateral edges at the rear of said sole while in that position and simultaneously with each beveling oper-

ation to cut a shoulder adjacent to said beveled edge.

7. A machine for operating upon a shoe provided with a short outsole having, in combination, means for supporting the outsole, and means for scarfing the bottom face of the outsole in fixed position adjacent to the opposite lateral edges of its shank end to provide heel-engaging surfaces tapering outwardly in directions transverse to the length of the outsole and forwardly from the rear extremity thereof.

8. A machine for operating upon a shoe provided with an outsole having, in combination, means for supporting the shoe, a pair of skiving knives for successively skiving opposite sides of the bottom face of said sole at the rear thereof, means for actuating said knives, and means for shifting one of said knives into operative position and the other of said knives out of operative position before each skiving operation.

9. A machine for operating upon a shoe provided with a short outsole which has a tongue at the shank end thereof having, in combination, means for supporting the shoe, separate supporting means for the portion of the sole adjacent to the corners formed at the opposite lateral edges thereof by the junction of the tongue and the shank end of the sole, and means for beveling the bottom face of the tongue toward said corners.

10. A machine for operating upon a shoe provided with a short outsole which has a tongue at the shank end thereof having, in combination, a movable skiving knife, a pair of supporting jaws arranged to engage opposite sides of the shoe, and separate means on each of said jaws for entering the welt crease of the shoe and holding said tongue in the path of said knife.

11. A machine for operating upon a shoe provided with a short outsole which has a tongue at the shank end thereof having, in combination, a movable skiving knife, a pair of supporting jaws arranged to engage opposite sides of the shoe, a supporting finger on each of said jaws for entering the welt crease of the shoe and holding said tongue in the path of said knife, and means for adjusting the position of said fingers relatively to said jaws.

12. A machine for operating upon a shoe provided with a short outsole which has a tongue at the shank end thereof having, in combination, movable skiving knives for removing stock from said tongue, a pair of supporting fingers arranged to enter the welt creases of the shoe and conjointly to support the projecting margins of the sole at the shank end thereof at one side of the path of said knives so that the knives will bevel the tongue to produce thin edges adjacent the shank portion.

13. A machine for operating upon a shoe provided with an outsole having, in combination, means for supporting a shoe, an oscillatory knife for operating upon said sole, and means for oscillating said knife transversely with respect to the sole to cut away a portion of the bottom face of the sole at the rear of said sole to form a new surface at a bevel to said bottom face.
- 10 14. A machine for operating upon a shoe provided with an outsole having, in combination, an oscillatory skiving knife for producing a convexly curved contour at the rear of the bottom face of said sole, means for oscillating said knife, and means for varying the path of movement described by said knife during its oscillation.
- 15 15. A machine for operating upon a shoe provided with an outsole having, in combination, means for shaping the rear of said sole to fit a recess in a heel to be attached to the shoe, said shaping means comprising a knife having two thin blades with their cutting edges angularly disposed toward each other, one of said edges adapted to cut away the bottom face at the rear of said sole and the other of said edges to form a shoulder adjacent to said cut away portion.
- 20 16. A machine for preparing a shoe provided with an outsole to receive a heel having, in combination, a knife having angularly disposed cutting edges, means for giving said knife a movement of translation transversely across the sole from its inner portion toward its periphery to cause one of said cutting edges to bevel a portion of the bottom face of the sole, while the other of said edges forms a rearwardly facing shoulder adjacent to said beveled portion.
- 25 40 17. A machine for operating upon a shoe provided with an outsole having, in combination, means for supporting a shoe, a knife having angularly disposed cutting edges, means for moving said knife transversely across the sole to cause one of said cutting edges to bevel a portion of the bottom face of the sole, and means for varying the position of said cutting edges longitudinally and angularly with respect to the sole during said transverse cutting stroke so that the other of said cutting edges will form a curved shoulder adjacent said beveled portion.
- 30 45 50 55 60 65 18. A machine for operating upon a shoe provided with an outsole having, in combination, means for supporting the shoe, a movable head, a knife carried by said head and having angularly disposed cutting edges, means for moving said head to cause one of said cutting edges to scarf the rear portion of the bottom face of the sole, and means for causing relative oscillatory and longitudinal movement of said knife during said movement of the head to cause the other of said cutting edges to form a curved shoul-
- der adjacent said scarfed portion of the sole.
19. A machine for operating upon a shoe provided with an outsole having, in combination, means for supporting the shoe, a movable knife, means for moving said knife transversely of the shoe to cut away the rear portion of the bottom face of the sole, and means for turning the knife and varying the direction of its cutting stroke sufficiently to produce a curved margin at one side of said cut away portion.
- 75 20. A machine for operating upon a shoe provided with an outsole having, in combination, means for supporting a shoe, a head adapted to swing laterally of the machine, a knife mounted on said head with provision for longitudinal movement relatively to the head and for oscillatory movement about an axis in a substantially vertical plane, means for imparting lateral swinging movement to said head to oscillate said knife about an axis in a substantially horizontal plane, and means for controlling the oscillatory movements of said knife in both planes as the head swings laterally.
- 80 85 90 95 100 105 110 115 120 125 130
21. A machine for operating upon a shoe provided with an outsole having, in combination, means for supporting a shoe, an oscillatory head, a knife carried by said head, means for oscillating the head, said means tending to cause said knife to describe an arcuate path of movement, means for shifting the head relatively to its axis of oscillation during its oscillatory movement so as to cause the knife to produce a convex curvature at rear of the bottom face of said sole which is non-circular in contour.
22. A machine for operating upon a shoe provided with an outsole which has a tongue at the rear end thereof having, in combination, means for supporting a shoe, a pair of skiving knives, oscillatory supporting means for said knives, means for bringing the cutting edges of said knives successively into position to operate upon said tongue, and means for oscillating said supporting means after each knife has been operatively positioned to move the knife transversely across the tongue so that the opposite lateral edges of the tongue will be successively beveled.
- 115 120 125 130
23. A machine for operating upon a shoe provided with an outsole having, in combination, means for supporting the shoe, an oscillatory head, a knife carried thereby, means for oscillating said head to impart a skiving movement of said knife transversely of the sole, means for moving said knife longitudinally of the sole during said skiving movement, and a gaging device for controlling said longitudinal movement and for causing said knife to turn about an axis at an angle to the axis of oscillation of the head.

24. A machine for operating upon a shoe provided with an outsole having, in combination, means for supporting the shoe, a head adapted to move laterally of the machine, a knife carried by said head, means for moving said head to impart a skiving movement to said knife transversely of the sole, means for moving said knife longitudinally of the sole during said skiving movement, a gaging device for controlling said longitudinal movement and for causing said knife to turn about an axis substantially perpendicular to the sole, and means for adjusting the position of said knife relatively to said gaging device.

25. A machine for operating upon a shoe provided with an outsole having, in combination, means for supporting the shoe, an oscillatory head, a knife carried by said head, means for oscillating said head to cause said knife to cut away a portion of the sole convexly, and means for causing radial movement of said head relatively to its axis of oscillation during its oscillatory movement so as to modify the cutting stroke of the knife.

26. A machine for operating upon a shoe provided with an outsole having, in combination, means for supporting the shoe, an oscillatory head, a knife carried by said head, means for oscillating said head to cause said knife to cut away a portion of the sole convexly, and a cam for causing radial movement of said head relatively to its axis of oscillation during its oscillatory movement so as to effect the swinging of the knife through a path not the arc of a circle.

27. A machine for operating upon a shoe provided with an outsole having, in combination, means for supporting the shoe, an oscillatory head, a knife carried by said head, means for oscillating said head to cause said knife to cut away a portion of the sole convexly, a flexible cam for causing radial movement of said head relatively to its axis of oscillation during its oscillatory movement so as to effect the swinging of the knife through a curved path, means for flexing said cam, and means for varying the flexure of said cam to modify the movement of the knife.

28. In a machine for operating upon a lasted shoe provided with an outsole, operating instrumentalities and means for supporting an inverted shoe comprising a back gage, a pair of gripper jaws for engaging the opposite sides of the counter portion of a shoe, and means for supporting the projecting marginal portions of the outsole adjacent to the opposite lateral edges at the rear of the outsole.

29. In a machine for operating upon a lasted shoe provided with a short outsole, means for scarffing the bottom face of the outsole at the shank end thereof, a back gage,

a pair of gripper jaws for engaging the opposite sides of the shoe to position it transversely with respect to the scarffing means, and a pair of supporting fingers severally mounted upon the gripper jaws and adapted to enter the welt crease to support the projecting marginal portions adjacent to the opposite lateral edges at the shank end of the outsole.

30. A sole-preparing machine for operating on shoes prior to the attaching of heels comprising, in combination, a device for supporting a last with a bottomed shoe thereon in inverted position, including a gage to position the shoe longitudinally and members to enter the welt crease on opposite sides of the shoe to support the rear end of the sole, a movable trimming device, including a cutter and a guide part, and a stationary guide member having a cam surface to engage the guide part of the trimming device and constructed and arranged for adjustment to guide the cutter about the periphery of the rear end of the sole to remove waste material therefrom to provide beveled heel-seat surfaces thereon fitting the corresponding surfaces of a heel.

31. A sole-preparing machine for operating on shoes prior to the attaching of heels comprising, in combination, a device for supporting in inverted position a shoe with an attached sole, a trimming device movable in a curved path from side to side of the shoe, and a stationary guide member on the machine having a curved surface to guide the trimming device to remove waste material from the rear end of the sole to provide heel-seat surfaces for engagement with and to support a heel.

32. A machine for operating on the sole of a shoe, to form a shoulder to seat against a superposed heel, comprising, in combination, a fixed support for a shoe, and cutting means to remove waste stock from the rear end of the sole to fit it to a cavity in a heel, said means including a device with a cutting edge extending generally perpendicular to the shoe bottom and movable transversely widthwise of the sole to form a shoulder, and said means also being arranged to bevel the sides of the sole adjacent to the shoulder.

33. A machine for operating on the sole of a shoe, to form a portion to seat against a superposed heel, comprising, in combination, a support for a shoe, and cutting means to remove waste stock from the rear end of the sole to fit it to a cavity in a heel, said means including a device with a cutting edge extending generally perpendicular to the shoe bottom and mechanism to move said device laterally of the sole with said edge held substantially erect to cut in a plane heightwise of the sole.

34. A machine for preparing a sole to receive a heel comprising, in combination, a

- 5 cutter having a pair of angular cutting members, and means to give them movements of translation widthwise of a sole to engage therewith and form a shoulder at the heel breast line and a beveled portion adjoining the shoulder and extending rearwardly thereof on each side of the sole. 70
- 10 35. A machine for preparing a sole to receive a heel comprising, in combination, a cutter having a pair of cutting members operable to cut transversely of the width of a sole to form a rearwardly facing shoulder at the heel breast line, and means for effecting a relative movement of the cutter and a sole 75
- 15 to cause said cutting action while maintaining substantially the same relation longitudinally of the sole. 80
- 20 36. A machine for preparing a sole to receive a heel comprising, in combination, a cutter having a pair of cutting members, means to move the cutter transversely of the sole to engage with opposite sides thereof to produce a shouldered breast-line cut, guiding means to predetermine the path of the 85
- 25 cutter widthwise of the sole, and means to vary said path of the cutter. 90
- 30 37. A machine for preparing the heel-seat of a sole to receive a heel comprising, in combination, a cutter having a pair of breast shoulder forming cutting members, means to move the cutter transversely of the sole to engage with opposite sides thereof, and guiding means to predetermine the path of the cutter through the sole material at the 95
- 35 rear of the shoulder formed by the cut. 100
- 40 38. A machine for preparing a sole to receive a heel comprising, in combination, means for supporting a shoe in fixed position, an angular knife, and means to move the knife bodily across the sole of said shoe to form a shoulder at the heel breast line and a beveled portion rearwardly of the shoulder. 105
- 45 39. A heel-seat fitting machine comprising, in combination, a cutter, and means for relatively guiding a shoe and the cutter, including two members formed with guiding surfaces curved in planes substantially at right angles to one another, to form on 110
- 50 the sole of the shoe a heel-breast cut which curves in three dimensions as described. 115
- 55 40. A heel-seat fitting machine comprising, in combination, a cutter, and means for relatively guiding a shoe and the cutter in a curved path constructed and arranged to form on the sole of the shoe a heel-breast cut which curves in three dimensions as described. 120
- 60 41. A heel-seat fitting machine comprising, in combination, a cutter to form a shoulder on the sole of a shoe at the heel-breast line, a stationary guide member having a surface relatively to guide a shoe and the cutter to control the shape of the heel-breast line as projected on a horizontal plane, and 125
- 65 a second stationary guide member having a surface relatively to guide the shoe and cutter to vary the depth of cut to control the shape of the shoulder as projected on a vertical plane. 70
- 70 42. A machine to trim the rear end of a short sole to fit it for the superposition of a heel recessed at its breast edge comprising, in combination, a cutter for removing waste stock from the short heel-seat surface of the sole rearwardly of the heel-breast line, and means relatively to move a sole and the cutter widthwise of the shoe to keep the cutter in a narrow groove extending transversely of the sole to trim both sides of the short heel-seat of the sole to fit the recess in the heel. 75
- 75 43. A machine to trim the rear end of a short sole to fit it for the superposition of a heel recessed at its breast edge comprising, in combination, a cutter for removing waste stock from the short heel-seat of the sole rearwardly of the heel-breast line, and means relatively to move a sole and the cutter widthwise of the sole including a guiding cam member to cause the cutter to trim the short heel-seat of the sole to fit the recess in the heel. 80
- 80 44. A machine of the class described comprising, in combination, a work-support, a tool and a tool-carriage movable relatively thereto, and stationary members to engage the carriage, one constructed and arranged to guide the carriage vertically and another horizontally, to move the tool in a three-dimensional curve. 85
- 85 45. A heel-seat fitting machine comprising, in combination, a work-support, a sole beveling tool and tool-carriage movable relatively thereto, a flexible member to engage the carriage to guide the tool for movement in a curved path to provide a heel-seat surface, and means to bend said member to vary the curvature of the path of the tool. 90
- 90 46. A sole-fitting machine comprising, in combination, a work-support, an oscillating head and a fitting knife carried thereby, a horizontal pivotal mounting for the head below the work-support, said head being formed with a portion overhanging the work-support to carry the knife and including a knife slide movable radially with respect to the pivotal mounting, and means operated by the machine for oscillating said head about its horizontal pivot mounting. 95
- 95 47. A sole-fitting machine comprising, in combination, a work-support, an oscillating head overhanging the work-support and a sole fitting knife carried by the overhanging part of the head and wholly above the work on said support, and a horizontal pivotal mounting for the head below the work-support. 100
- 100 48. A sole-fitting machine comprising, in 105
- 105
- 110
- 115
- 120
- 125
- 130

- combination, a work-support, an oscillating head behind the work support having spaced pivotal bearings arranged horizontally below the work-support, a knife and a knife-carrying device on said head overhanging the work-support and arranged to allow radial motion of the knife with respect to the bearings, and a flexible guiding device and a guide follower co-operating to control the radial motion of the knife.
- 5 49. A sole-fitting machine comprising, in combination, a frame, a work-support, an oscillating head mounted to swing about an axis in the frame below the work-support, a fitting knife supported on the head, a pair of sliding connections between the knife and the frame constructed and arranged to allow the knife radial motion and motion in a direction at right angles to the plane of oscillation.
- 10 50. A machine as defined by claim 49, in combination with a guide member to control the radial motion of the knife, and a spring and means operating in opposition to the spring for controlling the motion in a direction at right angles to the plane of oscillation.
- 15 51. A machine of the class described comprising, in combination, a work-support, a carrier oscillating in a transverse vertical plane relative to the longitudinal axis of the machine about a horizontal axis below the work-support, and a tool carrying member slidingly received in the carrier for motion substantially parallel to said horizontal axis and arranged to overhang work on the support.
- 20 52. A machine of the class described comprising, in combination, a shoe-support, a carrier oscillating in a vertical plane about a horizontal axis below the shoe-support extending longitudinally of a shoe on said support, a head on the carrier arranged to overhang work on the support, and means operated by the machine for oscillating said carrier.
- 25 53. A machine for fitting the breast end of the heel seat of an outsole having, in combination, a cutter for forming a shoulder at the breast line of the outsole, said cutter and sole being relatively movable to transfer the point of operation of the cutter across the sole widthwise thereof, and guiding means for controlling said relative movement constructed and arranged to cause said shoulder on the sole to be curved, in plan.
- 30 54. A machine for fitting the breast end of the heel seat of an outsole having, in combination, a cutter for forming a shoulder at the breast line of the outsole, said cutter and sole being relatively movable to transfer the point of operation of the cutter across the sole widthwise thereof, and guiding means for controlling said relative movement constructed and arranged to cause said shoulder
- 35 on the sole to be curved, in plan, and the transverse cut to increase in depth from the central part of the sole outwardly toward each side edge thereof.
- 40 55. A machine for fitting the heel end of an outsole having, in combination, a scarfing cutter, means for supporting the outsole in position to be operated upon by said cutter, and means to actuate said cutter in a path extending widthwise of the outsole to produce a scarfed margin having a breast wall convexly curved relative to the width of the outsole.
- 45 56. A machine for fitting the heel end of an outsole having, in combination, means for supporting the outsole, and a single cutting means for producing a convexly curved surface on said heel end and a transversely curved shoulder at the forward edge of said surface to fit approximately the breast of a heel to be attached to the shoe.
- 50 57. A machine for fitting the heel end of an outsole having, in combination, means for supporting the outsole, a scarfing cutter having an edge to produce a shoulder at the breast line, a support for said cutter constructed to permit movement having components extending both widthwise and lengthwise relative to the outsole, and means to guide said cutter in both directions of movement thereby to produce a cut of predetermined character.
- 55 58. A machine for fitting the breast end of the heel seat of an outsole having, in combination, a cutter having a cutting edge to produce a shoulder at the breast line on one face of the outsole, means for relatively moving the outsole and cutter to transfer the cutter widthwise of the outsole and simultaneously longitudinally thereof, and means for controlling the direction and degree of both movements.
- 60 59. A machine for fitting the heel end of an outsole having, in combination, means for supporting the outsole, a scarfing cutter having an edge to produce a shoulder at the breast line, a support for said cutter constructed to permit longitudinal movement thereof relative to the outsole, and a guiding cam convexly curved about an axis substantially normal to the face of the outsole for determining the path of the cutter as it moves laterally.
- 65 60. A machine for fitting the heel end of an outsole having, in combination, means for supporting the outsole, a scarfing cutter having an edge to produce a shoulder at the breast line, a support for said cutter constructed to permit lateral movement thereof relative to the outsole, and a guiding cam curved about an axis substantially parallel to the face of the outsole for determining the path of the cutter as it moves laterally.
- 65 61. A machine for fitting the heel-seat of the sole of a shoe having, in combination, a

sole trimming tool, mechanism automatically to move said tool in a predetermined path, and manually adjustable means to vary the shape of the path of a point on the operative periphery of the tool.

62. A machine for fitting the heel-seat of the sole of a shoe having, in combination, a sole-beveling tool, means to move said tool in a curved path, and auxiliary and manually adjustable means to vary the curvature of said path.

63. A machine of the class described having, in combination, a movable operating tool, means to guide said tool in a curved path lying in one plane, and independent auxiliary means to guide it in a curved path lying in a plane at right angles to said first plane.

64. A sole fitting machine having in combination, a sole cutting tool, a carrier for said tool having a cam roll associated therewith, a flexible guiding cam with which said roll co-operates to guide the tool through a path determined by the cam, and means under control of the operator for flexing the cam to alter its effective contour.

65. A sole fitting machine having, in combination, a cam in the form of a flexible strip, means for varying the cam contour of said strip in accordance with the requirements of the work to be done, a movable carrier having a roll guided by said cam, and a sole cutting tool on said carrier arranged to operate on the work through a curved path determined by variations of the cam contour.

66. A machine for operating on shoe bottoms comprising a crease guide for the heel portion of the shoe, a knife, and means to guide said knife for movement obliquely widthwise of the sole and transversely of its edge, to and from said guide.

67. A machine for operating on shoe bottoms comprising a guide for the shoe heel portion, a knife arranged to oscillate to and from said guide in a direction oblique to the surface of the sole engaging surface

thereof, said knife having a portion of its cutting edge arranged to bevel the sole edge and having another portion extending at an angle to the first named portion for forming a shoulder at the end of the cut.

68. In a machine for operating on shoe soles, an oscillatory knife edge cutter member operable to scarf a portion of the bottom face of the sole successively on opposite sides thereof, said knife cutting member having also another cutting edge for simultaneously forming a shoulder, adjacent to said scarfed portion, to fit the breast of the heel.

69. In a machine for operating on shoe soles, a scarfing cutter having two oppositely facing cutting edges, a cutter carrier above the face of the sole to be scarfed, and means for oscillating said carrier and the cutter to successively scarf opposite sides of the sole, one side with one edge and the other side with the other edge of said cutter.

70. In a machine for operating on shoe soles, a knife carrier above one face of the sole, an oscillatory member on which said carrier is supported adapted to swing a sole scarfing knife on said carrier in a curved path toward an edge of the sole, the sole scarfing knife supported by said carrier having two angularly disposed cutting edges one of which is adapted to scarf a portion of the sole face while the other forms a shoulder adjacent said scarf.

71. A machine for operating on shoe soles having, in combination, means for supporting the sole, means for removing waste stock from the rear end of the sole to fit a cavity in a heel including a cutter member located above the body portion of the sole when inactive but movable obliquely of the sole and transversely to its edge, and means for operating said cutter member to cause it to travel first from its inactive position through one edge of the sole and thereafter from its inactive position through the opposite edge of the sole.
